UNITED STATES PATENT OFFICE.

CHARLES H. ANDERSON, OF SEATTLE, WASHINGTON.

STEEL CAR.

1,083,176.

Specification of Letters Patent.

Patented Dec. 30, 1913.

Application filed March 27, 1911. Serial No. 617,156.

To all whom it may concern:

Be it known that I, CHARLES H. ANDERSON, a citizen of the United States, residing at Seattle, in the county of King and State of Washington, have invented a new and useful Improvement in Steel Cars, of which the following is a specification.

This invention relates to improvement in the construction of steel-car bodies, and, as to certain features, is in the nature of an improvement upon the car-body frame shown, described and claimed in Letters Patent of the United States No. 943,213, granted to me December 14, 1909.

My objects are to improve the construction of the car-body under-frame with a view to rendering it particularly light and capable of resisting great buffing and crushing strains; to facilitate the operation of constructing the car-body in separate integral sections which may be built up on forms and readily joined together, thereby materially reducing the labor and erecting costs; to so construct the car-body ends as to render them unique and attractive in appearance, and of few parts describing simple curves which may be easily formed with necessary accuracy; and to provide other improvements which not only render the car-body particularly strong, durable and attractive, but work great economy in the matter of cost of construction.

In the drawings—Figure 1, is a broken plan section of a car-body frame, having the entrances midway of its ends at opposite sides, the section being taken on line 1 in Fig. 3; Fig. 2, a bottom-plan view of the under-frame; Fig. 3, a broken side view of the body-frame; Fig. 4, an end elevation of the body; Fig. 5, an enlarged section taken on irregular line 5—5 in Fig. 1; Fig. 6, a broken detail plan-view taken at one of the roof-frame joints; Fig. 7, an enlarged broken section taken on line 7 in Fig. 5; Fig. 8, an enlarged broken section of the car-end taken on line 8 in Fig. 4; Fig. 9, a broken elevation of the upper portion of the car-end; Fig. 10, a section on line 10 in Fig. 8; and Fig. 11, a plan view of one of the end roof-corner plates.

The main sills of the under-framing are formed of channel beams 12 which extend around the ends of the car-body and terminate at opposite sides of the central doorways 13. Riveted against the upper and

lower sides of the channel beams 12 at each car-end are upper end-sill plates 14 and lower end-sill plates 15 which, with the channel beams, form box-sills of great strength and rigidity. Extending along the channel beams, and riveted to the upper edges thereof, are inwardly projecting side-sill plates 16, 16, also secured by rivets to the end-sill plates 14. Riveted to the ends of the side-sill plates and upon the end-portions of the beams 12 are strengthening plates 17; the plates 17 at opposite sides of each doorway being riveted at their inner edges to a short longitudinally-extending channel beam 18. Extending across and below the door-openings are depressed channel or angle-bars 19 secured at opposite ends against the under sides of the channel-beams 12. The opposite lengths of the channel beams 12 are tied together by the cross sills 20, 21, 22 and 23, and by the bolsters 24. Fastened against the under sides of the beams 12, 21, 20 and 18 are lower strengthening plates 17^a which with the upper plates 17 form a box construction of great strength. Fastened against the channel beams 12 and the channel bars 19 at opposite sides of the doorways are vertical strengthening plates 25. In the doorways 13 are steps of which the channel beams 18 form the top risers; the treads 26, 27 and riser 28 in each instance being formed of a single plate bent to shape. Each lower tread 27 is fastened upon the channel bar 19, and each upper tread 26 is fastened against the lower edge of the channel beam 18. At the opposite ends of each flight of steps are plates 29 forming side-cheeks secured to the cross-sills 20 and carrying angle-bars 30 fastened against the ends of the treads and risers of the steps. The joints between the ends of the cross-sills 22, 23 and the channel beams 12 are strengthened by gusset-plates 31.

In practice, the underframe formed of the parts described constitutes one practically integral section of the car-body, complete in itself in the sense that it is constructed separate and apart from the other portions of the car-body. It dispenses with the longitudinally-extending center and intermediate sills usually provided in car underframes. The box-end sills, and the channel beams 12 and 18, reinforced by the sill-plates 16, strengthening box-plates 17, 17^a, channel bars 19 and steps, form a frame presenting

sufficiently great resistance to buffing and drawing strains without the necessity of center and intermediate sills which tend to encumber the under-face of the car-body 5 and are for that reason, and on account of their added weight, objectionable. The beams 12 terminate at opposite sides of each doorway in the boxes formed by the upper and lower plates 17, 17^a, and adjacent end- 10 portions of the channel-beam sills 12, 18, 20 and 21, which boxes operate to distribute the buffing strains to, more especially, the heavy channel-beam sills 18. The drawing and buffing strains are distributed through 15 the box-ends to the opposite side-portions of the frame which, when constructed as described, are of great strength and are not weakened by the presence of the doorways. Any tendency of the channel beams 12 to 20 buckle under crushing strain is effectually resisted by the sill-plates 16, and these sill-plates form supports for the car-flooring.

Each side-frame of the car-body is constructed as a separate integral section and 25 is formed with T-bars which constitute posts, separating the window-openings and the door-openings, and form the roof-supporting car-lines. The T-bars 32 and 33 form, respectively, the center and side posts 30 of the doorways, and the T-bars 34 separate the window-openings. Extending from each door post T-bar 33 to the end of the side-frame is a truss-plate 35 fastened with rivets to the T-bars 33 and 34, and channel- 35 beams 12. At the opposite sides of each doorway 13 are upright-plates 36 each riveted to or forming an integral part of a plate 35. Extending the full length of the side frame over the window and door-open- 40 ings is an upper truss-plate 37. On the upper outer edge of each lower truss-plate 35 is a longitudinally-extending channel-bar 38 having an inclined upper face; and fastened to the lower outer edge of the upper 45 truss-plate is a Z-bar 39. The channel-bar 38 operates to stiffen the upper edges of the lower truss-plate 35 and forms a stiffening support for the window-sill plates 40 in the window-openings. The Z-bar 39 stiffens the 50 lower edge of the upper truss-plate 37, and, in practice, forms a housing for the upper edge of the upper window-sash or sashes as well as a watershed. At each door-opening the plate 37 and Z-bar 39 form the lintel, 55 and, being riveted to the upright-plates 36, constitute the top or compression cord of a truss-construction, of which the lower, or tension, cord is formed, more especially, by the channel-beam 18, and also by the chan- 60 nel-bar 19 and steps. This construction contributes greatly to the strength of the car-body at the door-openings.

The present car-body is designed to be fitted with side, or longitudinally-extending, 65 seats, from the door-openings approximately

halfway to the ends of the car and thence with cross-extending seats having an aisle between them. Riveted to each T-bar 34 is a gusset-plate for attachment to the sill-plate 16 of the underframe. The gusset- 70 plates 41 on the T-bars, or door-posts, 33 may be formed as shown in Fig. 5, and the gusset-plates on the T-bars 34 toward the ends of the car-body may be similar thereto. The T-bars, at opposite sides of the door- 75 posts, along which the side-seats are to extend, are provided with combination gusset and seat-supporting plates 42 which may be of the shape indicated in Fig. 5. The gusset- 80 plates 42 contribute quite materially to the strength and rigidity of the structure and dispense with other supporting means for the side-seats.

In practice, the side-frames consisting of the parts described are constructed upon a 85 suitable form, the tops or carline portions of the T-bars 32, 33, 34 terminating at the center of the roof-line. When the side-frames are assembled upon the underframe the ends of the opposite T-bars 32, 33, 34 90 abut and may be secured together by angle-plates 43. If desired, ornamental forged or malleable T-bar joining-pieces may be substituted for the plain angle-plates 43 illustrated, which pieces may, for example, form 95 attachments for bell-cord hangers or electric-lamp sockets.

The ends of the car are separately formed structures having the upright T-bars 44, provided at their lower ends with gusset- 100 plates for attachment to the box-sill plates 14, and a lower end plate 45. The T-bars 44 support the car-end hood consisting of the center-plate portion 46, and corner-plate 105 portions 47. The plate 46 is bent in the arc of a circle, forming, in effect, the quarter of a cylinder, while the corner-plates are dished to the arc of a circle of the same diameter, and constitute approximately one-fourth of a sphere. Thus, the plates 46, 47 describe 110 simple curves which are easily formed, and they join closely together at their meeting edges. Owing to the simple shape of the hood, the parts 46 and 47 may, if desired, be easily shaped from a single plate. Rising 115 from the hood-plates 46, 47, is a vertical end-plate 48 which may contain a designation sign opening 49 and signal-light openings 50. The plate 48 is flanged at its lower edge and riveted to the hood-plates 46, 47. 120 The upper circular edge of the plate 48 is adapted to fit closely within the head of the T-bar 34 which forms the end-carline.

To place an end in position it is riveted at its gusset-plates to the box-sill plate 14, 125 at its plates 45, 47 and 48 to the adjacent T-bars 34, and at its plate 45 also to the channel beam 12. The lower end-plate 45 thus abuts against the ends of the plates 35, forming, in effect, a continuation thereof. 130

Extending around the ends are the bars 38^a, 39^a, forming continuations of the bars 38 and 39.

The roof plates 52 may be secured to the carline before the side-frames are assembled upon the underframe and in that event would abut at the center of the roof-line. The joint at the center of the roof-line is covered by a cap-plate 53.

10 Constructed as described, the car-body is formed of five sections, namely, the underframe, the two side-frames, and the two end-frames which are separately built up on forms, and which, when assembled, fit properly together and constitute the entire car-body. Constructing the sections in this way permits the use of forms, which insure accuracy and interchangeability, and labor-saving machines and tools for punching, 15 riveting, etc., which could not be employed if the car-body were erected as a whole instead of in sections.

20 The foregoing description, of the car as I now prefer to construct it, has been given for clearness of understanding only, my intention being that no undue limitation 25 should be understood therefrom, and that the

claims which follow shall be construed as broadly as the prior state of the art may permit.

30

What I claim as new, and desire to secure by Letters Patent, is:

1. In a steel-car underframe, channel-bars extending around the edges of the car body and forming integral end and side sills, 35 inwardly projecting plates secured to the upper and lower sides of the end-sill portions of said channel-bars, and inwardly projecting plates secured to the upper edges of the side-sill portions of said channel bars. 40

2. In a steel-car, an underframe formed with channel-beam side and end sills, inwardly projecting upper and lower plates secured against the upper and lower sides of the channel-beam across the ends of the 45 frame and forming with the channel-beam an end box-sill, and inwardly projecting side sill-plates secured at their outer edges to the channel-beam and at one end to the upper box-sill plate.

CHARLES H. ANDERSON.

In the presence of—

R. A. RAYMOND,
J. G. ANDERSON.
